UNITED STATES PATENT OFFICE.

GEORGE FREDERICK BULL AND ERNEST WALTER STARKEY, OF BIRMINGHAM,
ENGLAND; SAID STARKEY ASSIGNEE OF HIS ESTATE TO CHARLES H. PUGH
LIMITED, OF BIRMINGHAM, ENGLAND.

POWER-DRIVEN LAWN MOWER.

Application filed April 24, 1922. Serial No. 556,319.

To all whom it may concern:

Be it known that we, GEORGE FREDERICK BULL and ERNEST WALTER STARKEY, subjects of the King of Great Britain, and both residing at Birmingham, England, have invented certain new and useful Improvements in Power-Driven Lawn Mowers, of which the following is a specification.

This invention relates to improvements 10 in power-driven lawn-mowers and the like, and refers more particularly to that type of machine wherein the power is transmitted from the engine-shaft to the shaft of the driving roller through an intermediate shaft, the three shafts being connected up by suitable driving media. The object 15 of the present invention is to provide a simple and efficient means for suitably adjusting the intermediate shaft relatively to 20 the other two shafts.

According to this invention we provide a lawn-mower of the type referred to wherein the intermediate shaft is supported by a member disposed at a suitable point in the 25 length of the said shaft; this member being capable of both a longitudinal movement and also of an angular movement about a point in the length of the same.

Figure 1 is a side elevation of a power-driven lawn-mower showing the invention 30 applied thereto.

Figure 2 is a part sectional plan of the same, and Figure 3 is a sectional view upon the line 3—3, Figure 2.

In carrying out the invention the engine 35 is mounted upon the framework 2 of the machine in any suitable and convenient manner.

Secured to one end of the engine-crank 40 shaft is a sprocket wheel 3 which drives, through the medium of a chain 4, another wheel 5 mounted upon an intermediate shaft 6. This latter shaft is disposed transversely 45 of the machine and extends from side to side thereof. Mounted upon one end of the said intermediate shaft and adapted to be connected thereto by a clutch 7 is a sprocket-wheel 8 which drives through the medium 50 of a chain 9, a sprocket wheel 10 keyed to the shaft 11 of the ground rollers 12.

The intermediate shaft is journaled in bearings located in a pair of members disposed longitudinally of the machine and adjacent either side of the same. Each of

these members comprises a long bar 13 having at a point between its ends an upstanding short arm 14 at right angles thereto, and it is in these arms that eyes 15 are formed for housing the aforementioned bearings. In one end of each of the said members an elongated hole 16 is provided the diameter of which is slightly larger than that of the transverse supporting element or tie-rod 17 bracing together the side-frames 18 of the machine, so that when the member is mounted upon the said tie-rod, as will be hereinafter explained, it will be free to pivot and move longitudinally in respect to the same, but no transverse movement will be permitted thereto. In the opposite end of each of the members a suitably shaped hole 19 is formed whose diameter is larger than that of the transverse supporting element or tie-rod 20 so that when the latter is passed through the hole 75 a considerable amount of movement is allowed the said member in all directions. The ends of the shaft supporting members in which the holes 19 are formed are provided with extensions 21 which are tied together by a rod 22 running transversely of the machine; by this means the movements of the members are controlled so that they take place simultaneously.

When the machine is assembled the engine is disposed vertically above the ground roller with the members 13 carrying the intermediate shaft between the engine and roller, the arrangement being such that the said shaft is disposed out of line with the engine shaft and the ground roller shaft, so that the three shafts form the points of a triangle (Figure 1). The said members 85 13 are mounted upon the tie-rods 17 and 20 which pass through apertures in the side members 18, the rod 17 also passing through the elongated holes 16 and the rod 20 through the holes 19, so that the members are thus permitted to move longitudinally 90 and also angularly in a vertical plane, the members pivoting about the rod 17 passing through the elongated holes. It is by a combination of these two movements that the chains connecting the engine shaft and lay shaft and the lay shaft and ground 100 roller shaft can be adjusted simultaneously, quickly and in a very simple manner.

To lock the members 13 in their adjusted

positions washers 23 are provided on either side of the holes 16, 19, these washers being pressed against the members 13 by means of distance sleeves 24 under the influence of nuts 25 screwed on to the ends of the rods, the side members 18 having sufficient resiliency to permit this locking action.

In order to allow the adjustment of the chains to take place without disturbing the clutch lever 26, the latter is pivoted to the tie-rod 22 connecting the extensions on the ends of the members carrying the lay shaft, the said lever thus moving with the latter during the operation.

Having fully described our invention, what we desire to claim and secure by Letters Patent is:—

1. A power-driven lawn-mower of the type referred to, having a frame member, an engine driven shaft, a ground roller shaft, and an intermediate shaft, said shafts being operatively connected, a supporting member for said intermediate shaft, and means connecting said supporting member to said frame member so as to permit endwise and angular adjustment of the said member.

2. A power-driven lawn-mower of the type referred to, having a frame member, an engine, a crank shaft driven by said engine, a roller supporting shaft, an intermediate shaft, a member connected to said frame member and supporting said intermediate shaft, said member having lengthwise and angular adjustment, sprocket wheels on said shafts, sprocket chains connecting said sprocket wheels, and means for locking said intermediate shaft in its adjusted position.

3. A power-driven lawn-mower of the type referred to having a frame, an intermediate shaft, a member supporting the said shaft, the said member having an elongated slot at one end thereof and an aperture at the opposite end for permitting limited movement of the member in all directions within a vertical plane, a transverse supporting element attached to said frame and passing through the elongated

slot, a second transverse supporting element attached to the frame and passing through the aforesaid aperture in the opposite end of the member, said last named element being of smaller diameter than the aperture, and means for locking the member in its adjusted position.

4. A power-driven lawn-mower of the type referred to having apertured frame members, an intermediate shaft, a supporting member for said intermediate shaft, the said member having an elongated slot at one end thereof, an aperture at the opposite end suitable for permitting movement of said member in all directions within a vertical plane, a transverse tie-rod passing through the elongated slot so that the member can be adjusted endwise thereon, a second transverse tie-rod passing through the aforesaid aperture in the opposite end of the member, the said last named tie-rod being of smaller diameter than the aperture, said tie-rods passing through the apertures in said frame members, washers upon the tie-rods upon each side of the supporting member, distance sleeves upon the tie-rods between said frame members and said shaft supporting member, and means upon the tie-rods for pressing the distance sleeves against the washers so that the latter lock the shaft supporting member in its adjusted position.

5. A power-driven lawn-mower comprising a frame, an engine mounted on said frame, a roller carrying shaft on said frame and beneath said engine, a crank shaft driven by said engine, an intermediate shaft, members supporting said intermediate shaft mounted on said frame for longitudinal and angular adjustment and means for locking said members in adjusted position.

In testimony whereof they have hereunto set their hands in presence of two subscribing witnesses.

GEORGE FREDERICK BULL,
ERNEST WALTER STARKEY.
